COMPUTING MACHINE

Arthur C. Seymour, Frankfort, N. Y., assignor to
Remington Rand Inc., Buffalo, N. Y., a corpora-
tion of Delaware

Application January 7, 1935, Serial No. 581

3 Claims. (CL 235—59)

My invention relates to calculating or computing machines, and especially to combined typewriting and computing machines having algebraic totalizers and clearance proof mechanism.

- 5 One of the principal objects of my invention, generally stated, is to provide an improved and highly efficient clearance proof mechanism for algebraic totalizers which will test for both positive and negative clearance.
- 10 Another object of my invention is to provide an improved positive and negative clearance proof mechanism which can be readily incorporated in an algebraic totalizer without materially modifying said totalizer.

- 15 A further object of my invention is to provide a positive and negative clearance proof mechanism which operates independently of the shutter control in the totalizer.

More specifically, it is an object of my invention to provide a positive and negative clearance proof mechanism which comprises a feeler for each of the positive and negative sets of numeral dials in the totalizer, and a resetting arm for each of said feelers and cooperating independently therewith.

25 A still further object of my invention is to provide a separate and independent train of operating connections between each of the two independent resetting arms and its feeler, and in which the parts of each train are maintained constantly in operative connection and are automatically controlled to automatically and selectively control the movement of the resetting arms into and out of operative position.

30 To the above and other ends which will hereinafter appear my invention consists in the features of construction, arrangements of parts and combinations of devices set forth in the following description and particularly pointed out in the appended claims.

40 In the drawings wherein like reference characters designate corresponding parts in the different views:

Fig. 1 is a vertical fore and aft sectional view through an algebraic cross totalizer constructed in accordance with my invention and showing the clearance proof mechanism set for a negative clearance;

Fig. 2 is a fragmentary fore and aft vertical sectional view of part of the mechanism illustrated in Fig. 1 and showing the clearance proof mechanism set for positive clearance;

Fig. 3 is a fragmentary vertical sectional view taken along the line 3—3 of Fig. 1 and looking in the direction of the arrows at said line;

Fig. 4 is a horizontal sectional view of the totalizer taken along the line 4—4 of Fig. 1 and looking in the direction of the arrows at said line;

Fig. 5 is a detail perspective view of the connecting disc for the positive clearance proof mechanism;

Fig. 6 is a detail perspective view of the special carrying wheel for the "fugitive 1" mechanism;

Fig. 7 is a detail perspective view of one of the regular carrying wheels of the totalizer;

Fig. 8 is a detail perspective view of the feeler comb for the positive clearance proof mechanism; and

Fig. 9 is a fragmentary perspective view of an algebraic totalizer embodying my invention, showing some of the other operating parts of a combined typewriting and computing machine associated therewith.

In all of the views the parts are shown on an enlarged scale.

My invention may be regarded, in some respects as an improvement on the general types of clearance proof mechanism shown and described in Patent No. 1,490,129 to Arthur F. Poole, No. 1,490,989 to Carl A. Sieweck and No. 1,491,898 to Robert G. C. Boa. In the Poole patent clearance testing mechanism is provided which is adapted to show clear whether the reading is from positive numeral dials or from negative dials; and the mechanism comprises a single feeler which coacts with the intermediate gears of the totalizer and may be shifted to either of two positions for positive or negative clearance. The Boa patent discloses mechanism for the same purpose which comprises a sort of double feeler device pivoted to swing about an axis through the central portion thereof and adapted to be swung into engagement with one gear of each denominational gear train in order to test for positive zero, and adapted to be swung in the opposite direction into engagement with another gear of each denominational train in order to test for negative zero. According to the Sieweck patent which attains the same general ends, two different feelers are provided, one of which cooperates with one wheel in each denominational train to test for positive zero, and the other of which cooperates with another wheel of the same train to test for negative zero.

In all of the above constructions one resetting arm coacts with the feeler or feelers used. Furthermore, since only one resetting arm is employed, it is necessary to provide a selecting mechanism which either will shift the feeler or the connections to the resetting arm when the total-

izer changes from a positive to a negative state. In each instance this is rather a delicate and complex mechanism which coacts with the lever employed to shift the shutters used in conjunction 5 with the positive and negative numeral dials.

According to my present invention I provide in 10 an algebraic totalizer having a train of gearing for each denomination a mechanism of the same general type referred to above, which comprises 10 15 a resetting or control arm coacting with a feeler which in turn cooperates with one wheel of each denominational train to test for positive clearance; and a second resetting arm coacting with a second feeler which is adapted to cooperate with 15 another wheel in each train to test for negative clearance. Since two resetting arms are employed I am enabled to eliminate the use of the above described selecting mechanism cooperating 20 with the shutter control lever, and thereby provide a simple and highly effective positive and negative clearance testing device in which there is a separate and constantly maintained train of connections between each resetting arm and its feeler, as will hereinafter more clearly appear.

25 The drawings in the present case represent the invention in the form in which it is embodied in combined typewriting and computing machines, such as are known as Remington accounting and bookkeeping machines. The construction and 30 operation of such machines, not including the clearance proof mechanism, is explained in Patent No. 1,270,471 to J. C. Wahl, to which reference is made for a disclosure of any mechanism which the drawings in the present instance do not show 35 and which Remington accounting machines include, or any mechanism which is particularly referred to but not fully illustrated herein. It should be understood, however, that the invention is not restricted to its use in such machines 40 but may be applied to different forms of calculating or computing machines of this same general type wherever found available.

The Remington accounting machine is so well 45 known and the calculating mechanism of it so well described in the Wahl patent above referred to, that I have illustrated only those parts of the machine which immediately cooperate with the devices of the present invention.

In many of the previous algebraic totalizers, as 50 for example that shown in Patent No. 1,753,711 to L. S. McCorn, dated April 8, 1930, there are two sets of numeral dials. In such totalizers the upper set of numeral dials is generally used to show positive totals and the lower set is used to 55 show negative totals. However, in the totalizer in which my invention has been embodied, this construction has been reversed and the upper set of dials is used for registering negative totals and the lower set of dials is used for positive totals. The reason for this change resides in the fact 60 that in practice it was found that the lower set of dials is more readily visible by the operator. Therefore, since in most forms of work positive totals occur more frequently than negative totals, it has been found advantageous to reverse the former construction and use the lower set of 65 numeral dials for the registering of positive totals.

70 I shall first describe the general construction of the totalizer, and will follow this with a description of the positive and negative clearance proof mechanism made in accordance with my invention.

75 The Remington accounting machine includes

a Remington typewriter having mounted on its frame the Wahl calculating mechanism, the latter including among its several parts the usual cross truck 10, as shown in Figs. 1 and 9. Secured to the cross truck 10 by a latch lever 11 is 5 the cross totalizer which is designated as a whole by the reference numeral 12. The framing of the totalizer itself comprises a right-hand side plate 13, a left-hand side plate 14 and various connecting rods and bars 15 secured at their ends 10 by any suitable means to these side plates and extending transversely between them. Top and front cover plates 13a and 14a respectively are secured to some of the cross rods 15 by means of screws 15a as shown in Figs. 1 and 9. 15

As is well known, the ordinary Remington or Wahl totalizer is operated one denomination at a time. The wheels in each denomination comprise a carrying gear or wheel 16 mounted on a fixed pivot rod 17, an intermediate or idler gear 18 mounted on a fixed pivot rod 19, and a pinion 20 rigid with a dial 21 on which the amounts are read, both said pinion and said dial being mounted on a fixed pivot rod 22. The transfer mechanism is of the so-called "Geneva" type and it includes the usual stop works or transfer gears 23 each mounted on a lever 24 having a lower projecting end 24a. The levers 24 are of two kinds pivoted on frame rods 25 and 26 respectively, and at their upper ends they all normally rest against 30 stop screws 27 and cooperate with a universal locking bar 28. In operating the totalizer one denomination at a time the register wheels and transfer mechanism are controlled by an actuator which comprises a master wheel 29 (Fig. 1) 35 adapted to be successively engaged by the carrying wheels 16 as the cross totalizer receives a step-by-step advance movement with the main carriage; and at such time a master dog 30 registers successively with the lower projecting ends 40 24a of the transfer levers 24. The fragmentary illustration of these two parts 29 and 30 in Fig. 1 is intended as a conventional representation thereof as employed in the Remington or Wahl actuator. 45

As stated above, in some totalizers of this same general type it has been customary to have the upper set of dials, in the present instance the dials 21, register the positive numbers. However, in the present embodiment of my invention the 50 dials 21 are used to register the negative numbers, and there is provided an additional set of pinions 31 having dials 32 for the registering of the positive numbers. The pinions 31 and the dials 32 are carried on a fixed pivot rod 33 and 55 said pinions are arranged to mesh with the idler gears 18. Each of the positive or lower dials 32 contains the numerals "0" to "9" arranged on the periphery thereof in counter-clockwise order. The numerals on the dials 21 are arranged in 60 reverse order to those on the dials 32 and are so set that when a "0" shows through a lower sight opening 34 a "9" will show through an upper sight opening 34a or vice versa, both of said sight openings being provided in the front cover 65 plate 14a.

For the purpose of displaying the proper total, positive or negative, as the case may be, and to conceal from view the other totals, there are provided two shutters 35 and 36 for the dials 32 70 and 21 respectively. These shutters are in the form of bails having arms pivoted on the fixed pivot rods of the dials they are to cover. On the pivot rod 19 of the idler gear 18 there is pivoted a lever 37 (Fig. 2) having an arm 38 which projects 75

through a slot 38^a (Fig. 9) in the front cover plate 14^a and serves as a handle for turning said lever. This lever is provided with two pins 39 and 40 which are located forward of the pivot rod 19 and one on either side of the handle 38. The pin 39 projects into a slot 41 provided in an arm 42 on the shutter 36, while the pin 40 projects into a slot 43 provided in an arm 44 on the shutter 35. The arrangement of the above described shutters 35 and 36 and lever 37 cooperating therewith is such that when the handle 38 is in its lower position, as shown in Fig. 2, the shutter 35 will be out of registry with the sight opening 34 so that a positive total may be observed, whereas the shutter 36 will register with the opening 34^a. When, however, the arm 38 is moved to its upper position, the shutters 35 and 36 will move to the positions shown in Fig. 1 where the shutter 35 is moved away from the sight opening 34^a, and allow a negative total to be observed, while the shutter 36 extends across the opening 34.

At its inner end the lever 37 is formed with a series of gear teeth 45 which mesh with a series of gear teeth 46 on an operating wheel or disc which is designated as a whole by the reference numeral 47, and is shown detached and in perspective in Fig. 6. This disc or wheel is pivoted on the pivot rod 17 of the carrier gears 16 just to the right of the carrier gear of lowest order.

The wheel 47 has for its purpose the carrying to the gear 16 of lowest order, the so-called "fugitive 1", which must be subtracted or added every time an algebraic totalizer changes from a positive to a negative total, or vice versa. The construction of this wheel is very similar to that of a carrying gear 16, for like said gear 16 it is made, in the present instance, in three planes or strata. The right-hand strata of the carrying gear 16 includes the usual 30 teeth, whereas in the corresponding strata of the wheel 47 there are the teeth 46 which mesh with those provided on the lever 31. For the purpose of comparison the two wheels 47 and 16 are shown in perspective in Figs. 6 and 7 alongside one another so that their similarities may be noted. In the middle plane of the wheel 16 there are three transfer teeth 48 but on the wheel 47 there is only one transfer tooth which is designated as 48^a. The left-hand plane of both wheels consists of a locking disc having a circular perimeter designated as 49 in the wheel 16 and as 49^a in the wheel 47. The perimeter 49 is broken by notches 50, one for each transfer tooth 48, and likewise the perimeter 49^a is provided with a notch 50^a for its transfer tooth. It will be noted that the transfer tooth 48^a is integral with a flange 51 in the plane of the teeth 46, and by such a construction is given greater strength and rigidity. A lever 24 and transfer gear 23 are provided to operatively connect this wheel 47 with carrying gear 16 of lowest denominational order in much the same way that one of said gears 16 is operatively connected through transfer mechanism with the gear 16 of the next higher order, as is well known in totalizers of this kind. It will be perceived that whenever the handle 38 is moved upward from the position shown in Fig. 2, the tooth 48^a of the wheel 47 is turned in a counter-clockwise direction a distance sufficient to turn the usual star wheel 52 of the associated transfer or "Geneva" gear 23 the distance of one tooth, with the result that the companion gear 16, and in fact the whole gear train of lowest order will move one tooth in subtracting direction. When said handle is then moved downward, the

wheels turn in an adding direction back to normal position.

In order to limit the extent of the rocking motion of the wheel 47 in both directions, a pin or stud 53 (see Figs. 1 and 2) is riveted in the side plate 13 and projects into the plane of the wheel 47. The right-hand stratum of said wheel is cut away so as to leave two lugs 54 and 55 in such position that one of them engages the stud 53 to arrest the wheel when moving in one direction, and the other engages the stud when said wheel is moving in the other direction.

In order to retain the parts in one or the other of their two positions two notches 56 and 57 are provided in the periphery of the wheel 47 to receive and cooperate properly with a V-shaped nose 58 (see Figs. 1 and 2) on a detent lever 59 which is pivoted on the rod 25 and drawn downward by a spring 60, similar to those which act on the levers 24. The detent lever 59 is made similar to those usually employed in the Wahl totalizer to control the register wheel of lowest order. This lever is riveted, as at 61, to the side of a longer lever 62, which is somewhat like the levers 24 except that it does not carry a gear 23, but at its free end cooperates like the levers 24 with a stop screw 21 and the universal locking bar 28. The spring 60 which tends to pull the V-shaped nose 58 into one of the notches 56 or 57 is attached at one end in an opening 63 in the lever 62 and at its other end to a rod 64 which also constitutes an anchorage for the springs that are used in conjunction with the levers 24. The foregoing construction is such that when the handle 38 is operated the motion of the wheel 47 cams the nose 58 out against the force of the spring 60 until the turning of the wheel is nearly completed when said nose is drawn downward by the spring 60 into the notch 57 to complete the motion of the parts to, and retain them, in shifted 40 position.

Having thus described the construction of the algebraic totalizer in which my invention may be embodied, I shall now describe the positive and negative clearance proof mechanism used in combination therewith. In the present instance the upper set of numeral dials is used exclusively for the registering of negative numbers and therefore, the mechanism cooperating with the numeral dials of the upper set will show or indicate 50 a negative proof of clearance. This mechanism comprises a feeler comb 65 pivoted at 66 in the side plates of the cross totalizer, and when the dials 21 register zero said feeler engages a short tooth 67 provided on each of the numeral dial 55 gears 20. This feeler comb 65 is constructed and operated substantially like the comb 75 shown in Fig. 8, and a more detailed showing thereof than that included herein is therefore deemed unnecessary. Extending rearward from the pivot 60 of the feeler comb 65 is an arm 68 having a rounded end portion 68^a. A second arm 69 is pivoted on the pivot rod 28 and extends forward therefrom being bifurcated at its forward end to receive the rounded end portion 68^a and provide 65 an operative connection between the arms 68 and 69. The arm 69 is drawn upward by a spring 70 which is attached at one end to said arm and at its other end to a cross bar 71 fixed in the side plates of the totalizer. This upward movement 70 of the arm 69 is transmitted to the arm 68 and tends to turn the feeler comb 65 in a counter-clockwise direction (Fig. 1) to press said feeler against the teeth of all of the pinions 20. The arm 69 is one arm of a bell crank, the other arm 75

72 of which constitutes a finger, resetting arm or control member which projects upward through an opening 73 provided in the top cover plate 13^a of the totalizer. This finger cooperates with other mechanism mounted on the stationary frame work of the machine, which mechanism may be of any suitable type, as for example, a star proof of clearance mechanism of the sort shown in the patent of F. A. Hart No. 1,737,586 dated Dec. 3, 1929. One form of this cooperating mechanism will be hereinafter more fully described.

Referring now to the dials 32 for registering positive numbers it will be recalled that said dials occupy a new position in the lower portion of the totalizer. In order to take care of the proof of clearance of positive numbers, it has been found desirable to provide a second and independent feeler cooperating with this lower or positive set of numeral dials. This positive proof of clearance mechanism will now be described.

Arranged below the dials 32 and in a position to cooperate with the teeth of all of the pinions 31 is a second feeler comb 75. This feeler comb 75 is shown in perspective in Fig. 8 and comprises the usual axis or shaft 76 provided at its ends with lugs 77 and 78 by which it is pivoted into the side plates of the totalizer. A web or supporting plate 79 extends radially forward from the shaft 76 and is provided with the usual ribs 80. These ribs correspond in number to the number of dials in the totalizer and are so positioned in said totalizer as to be capable of cooperating with the teeth of all of the pinions 31. One tooth 81 of each of the pinions 31 is made short, and each tooth 81 registers and cooperates with an associated rib 80 on the comb 75 when all of the dials 32 stand at zero, as shown in Fig. 2. An arm 82 is fastened to the right-hand end 40 of the comb 75 (left-hand end as shown in Fig. 8) and projects rearward therefrom. A rounded portion 83 is provided at the end of the arm 82 which is received in a notch or indenture 84 provided in the periphery and at the left-hand side 45 of a connecting disc 85, as the parts are shown in Fig. 2. This disc 85, which may be provided with a hubbed bearing 85^a is mounted on the pivot rod 17 to the right of the wheel 47 and separated therefrom by a spacing sleeve 85^b as shown in Fig. 4. The hubbed bearing 85^a constitutes a means for holding the disc away from the side plate 13. A notch 86 similar to the notch 84 is provided in the disc 85 substantially diametrically opposite the notch 84. Received in the notch 86 is a rounded engaging portion 87 provided on the forward end of an arm 88 which is pivoted on the pivot rod 26. A spring 89 attached at one end to the arm 88 and at its other end to the connecting rod 11 tends to move the arm 88 upward about the pivot 26. Such movement of the arm 88 turns the disc 85 in a counter-clockwise direction, as the parts are shown in Figs. 1 and 2, which results in an upward movement of the ribs 80 of the feeler comb 75 tending 55 to press said ribs against the teeth of all the pinions 31. The arm 88 is one arm of a bell crank, the other arm 90 of which constitutes a second finger, resetting arm or control member which projects upward through the opening 73 in the top cover plate 13^a of the totalizer. This finger or resetting arm 90 is similar in construction and function to the resetting arm 72 and is arranged adjacent thereto but differs from said arm 72 in that it controls the lock for positive

clearance, while the arm 72 is used for negative clearance.

It is to be understood that each of the two fingers or resetting arms 72 and 90 may oscillate between two positions, one in which the finger occupies a rearward effective or operative position and the other a forward ineffective position. These two positions are controlled by the associated feeler combs which in turn cooperate with and are controlled by the teeth 10 of the dial pinions; the pinions 28 controlling the comb 65 and resetting arm 72 and the pinions 31 controlling the comb 75 and resetting arm 90. When either feeler comb engages all of the short teeth provided on the associated pinions at the zero position of the dials, the associated finger or resetting arm will occupy its rearward, effective or "clear" position. When either feeler engages any of the other teeth on the associated pinions, the companion 20 resetting arm or finger will occupy its other or ineffective position, which may be termed the "not clear" position. In Fig. 1 the arm 72 for the upper or negative set of dials is in the "clear" position while the arm 90 is in the "not clear" 25 position. Fig. 2 shows the reverse of this with the arm 90 in "clear" position and the arm 72 in "not clear" position.

Referring more particularly to Fig. 9 it will be seen that the mechanism cooperating with 30 either of the fingers 72 or 90 includes a frame plate or bracket 91 secured to the ends of the usual computing mechanism actuator frame casting (not shown). A lever 92 is pivoted to this plate at 93 and is given a normal tendency 35 to move down at its left-hand end or turn in a counter-clockwise direction about the pivot 93 by a spring 94. At the outer or left-hand end the lever 92 has an ear 95 bent off laterally therefrom and having in it a notch 96 which receives 40 an edge of the bracket 91 to guide said lever in its up and down movements. Secured to and off-set from the lever 92 by means of the connecting studs 97 is a cam bar 98 having at its left-hand end an inclined edge 99. This cam 45 bar 98 is so situated that when either of the fingers 72 or 90 is in its rear or "clear" position, and when the cross totalizer jumps to the right after the completion of an entry which clears the totalizer, the finger in "clear" position will 50 strike the incline 99 and raise the lever to the position shown in Fig. 9.

By raising the member 92, 98 in the manner described a release of the star printing key from its lock in the usual manner or an automatic 55 imprint of the clearance proof star will be effected as will hereinafter more clearly appear. If on the other hand the totalizer is not "clear" the fingers 72 and 90 will be in the forward ineffective position and will pass in front of the bar 98 on the return of the totalizer and leave the member 92, 98 in its normally depressed position, thus conditioning the machine to lock the star key as will presently appear.

A lever 100 is pivoted at 101 to the actuator 65 frame casting and at its right-hand end is bifurcated or forked at 102 to embrace the ear 95 on the lever 92 so that said lever 100 may be rocked up and down by the lever 92. Said lever 100 has a depending branch or arm 103 terminating in a tongue or locking finger 104 which passes through a suitable guide hole 105 in the usual frame plate 106. When the lever 100 is 70 in its elevated or "clear" position, the end of the finger 104 occupies a position just inside the 75

plate 106 and does not project leftward therefrom. However, when said lever 100 drops to its lower or "not clear" position, the finger 104 projects through the opening 105 a short distance leftward from said plate 106.

Lying flat against the outer side of the plate 106 and pivoted thereto at 107 is a bell crank 108, having a rearwardly extending arm 109 and an upwardly extending arm 110. The arm 109 of the bell crank is connected by a link 111 with the key lever 112 having a key 113 which when depressed effects the printing in the usual manner through the sub-lever 114 connected with said key lever and the type bar that prints the star of the clearance proof signal or symbol, which in the present instance is a star, as shown on the key 113. The upwardly extending arm 110 of the bell crank 108 normally occupies a position immediately in front of or adjacent the opening 105 in the plate 106, but is adapted to swing rearward over said opening when the key 113 is depressed. If, however, the levers 92 and 100 are in their depressed positions, the locking finger 104 will be projecting into the path of the arm 110 to lock said arm and the associated key 113 against operation. During that step of the carriage which follows the writing of the last digit of a balance, the cross truck 10 makes its jump to the right as usual. If the writing of the balance has brought the dials of the totalizer to either positive or negative zero, either of the fingers 90 or 72 will cam up the lever 92 withdrawing the finger 104 to ineffective position thus unlocking the star key so that the star can be written in the next letter space position. However, if the operator has not copied the total correctly, the lever 92 will not be raised and the star key will remain locked. Such a condition indicates to the operator that some error has been made.

In the light of the foregoing description it will be apparent that by my present invention I have provided a highly efficient and improved clearance proof mechanism for an algebraic totalizer in which there is a separate and independent train of connections between each set of dials and the associated resetting arm; in which the elements of each train are positively connected and that such connection is constantly maintained and operated entirely independently of the elements of the other train; wherein the mechanism is comparatively simple and may be readily incorporated in existing totalizer constructions without modifying, or materially modifying the existing structural features thereof; and wherein the control of the resetting fingers 90 and 72 for positive and negative clearance respectively is automatically effected without the actuation of a manually controlled part connected therewith.

It also will be observed that the algebraic totalizer is provided with a lower set of numeral dials for

showing positive amounts and a second or upper set for showing negative amounts. It is to be understood that this mechanism functions in conjunction with means for preventing the printing of a clear signal when the totalizer is not clear.

It is also to be understood that according to my present invention, the provision of two resetting arms eliminates the use of any selecting mechanism cooperating with the shutter control 10 lever, and hence provides a much simpler device capable of attaining all the ends specified.

Various changes may be made in the construction, and certain features thereof may be employed without others, without departing from my invention as it is defined in the accompanying claims.

What I claim as new and desire to secure by Letters Patent is:

1. In a calculating machine, the combination of a group of register wheels including an upper set of numeral dials for indicating negative totals and a lower set of numeral dials for indicating positive totals, a set of gears for each set of said dials, and proof of clearance mechanism comprising a feeler arranged to act on said gears for the positive dials, a second feeler arranged to act on said gears for the negative dials, and a pair of resetting arms, one of said resetting arms cooperating with said first mentioned feeler to control for positive clearance, and the other of said arms cooperating with said last mentioned feeler to control for negative clearance.

2. The combination with an algebraic totalizer having a train of gearing for each denomination, of clearance proof mechanism including a positive clearance proof device comprising a resetting arm and a feeler controlling said arm and cooperative with one wheel of each denominational train, and a negative clearance proof device comprising a second resetting arm and a second feeler controlling said arm and cooperative with another wheel of each denominational train.

3. The combination with an algebraic totalizer having a train of gearing for each denomination, of clearance proof mechanism including a positive clearance proof device and a negative clearance proof device; said positive device comprising a feeler cooperative with and controlled by one wheel of each train, a controlling arm, and a connecting device mounted concentrically with another wheel in one of said trains and effecting a positive and constantly maintained connection between said feeler and said arm; and said negative device comprising a second feeler cooperative with a third wheel in each train and positively and constantly connected with a second controlling arm.

ARTHUR C. SEYMOUR. 60
